UNITED STATES PATENT OFFICE.

LAWRENCE A. OLWELL, OF MILWAUKEE, WISCONSIN.

BRIEF-CASE.

1,261,159.

Specification of Letters Patent.

Patented Apr. 2, 1918.

Application filed July 9, 1917. Serial No. 179,326.

To all whom it may concern:

Be it known that I, LAWRENCE A. OLWELL, a citizen of the United States, and resident of Milwaukee, in the county of Milwaukee and State of Wisconsin, have invented certain new and useful Improvements in Brief-Cases; and I do hereby declare that the following is a full, clear, and exact description thereof.

10 My invention relates to certain new and useful improvements in brief bags, cases and the like, and has for its primary object to simplify the construction of such devices by so disposing the handles thereof as to cause the same to be attached to the sides of the device and not to the cover or flap, at the same time so arranging the flap or cover as to permit one handle to pass through the same and to avoid the necessity of using 15 clasps or other locking means or buckles to keep the cover or flap in place to permit of the same being carried by a handle attached thereto, and to avoid the bracing of the cover or flap for the attachment of the handle, thereby lightening the device, cheapening 20 its construction, enlarging its stability and simplifying the method of opening and closing the same.

Another object of my invention is to 25 avoid the wear and tear attendant upon the use of straps and buckles, locks and other closing devices made of metal and to save the time necessary in the ordinary manipulation of them, as applied to brief cases or bags, in their heretofore familiar construction.

A further object of my invention is to give to the device such simplicity of construction as tends as a result thereof to a 30 more finished and better appearing article of merchandise, at the same time adding to its stability and convenience in use.

A still further object of the invention is to provide a brief case or the like capable 35 of being opened while supported by one of its handles, whereas in brief cases and the like now in use, it is necessary that the same be rested upon a suitable support before being opened.

With the above and other objects in view, which will appear as the description proceeds, my invention resides in the novel construction, combination and arrangement of parts substantially as hereinafter described 40 and particularly defined in the appended claims.

In the accompanying drawings I have illustrated one complete example of the physical embodiment of my invention constructed according to the best mode I have so far devised for the practical application of the principles thereof, in which:

Figure 1 is a perspective view thereof, the flap cover being shown extending upwardly therefrom.

Fig. 2 is a side elevation of my brief case, the flap cover being in normal position covering the brief case, and

Fig. 3 is a transverse sectional view therethrough on the line 3—3 of Fig. 2.

In the present embodiment of my invention, as exemplified in the drawings, the numerals 5 and 6 represent the respective sides of the case which has the closing end members 7 and the intermediate partition 8 dividing the case into sections. The case is further provided with the usual handles 9 secured one on each side of the case in the ordinary manner, and the side 5 is continued outwardly from the case, as at 10, to provide a flap forming the cover for the brief case.

The flap 10 is adapted to pass over the brief case as depicted in Figs. 2 and 3, and has its end tucked in a pocket formed by the side 6 and member 11 secured thereto. In order to permit the passage of the flap over the handle carried by side 6, a substantially U-shaped cut is made in the flap, as at 12, and near the inner ends of said cut are the slotted or widened openings 13 forming handle receiving openings.

As will be seen by reference to Figs. 2 and 3, this cutaway portion allows the handle carried by side 6 to be outward of the cover when the same is folded over the brief case and when the cover is in this position, the flap 14 formed by the cut 12 is passed under the handle carried by side 6 and secured by a suitable clasp or other fastening 95 carried by the free end of said flap to the 100 adjacent edge of said cutaway portion.

Thus by the foregoing manner of constructing my case or bag I dispense with the usual faulty manner of securing the handle to the flap or cover which necessitates the 105 use of a brace to retain the shape of the bag and avoid a drag upon the fastenings when the case is being carried closed, and with the use of locks, clasps, buckles and straps to keep the bag closed, and make carrying by 110 the handle possible by securing two handles properly to the sides of the case and

thus equally distributing the strain and adding to its strength and durability, and appearance in use, as will be obvious.

While in the present exemplification of my invention I have illustrated the same in use with what is termed a brief case, it will be appreciated that the same may be used on a portfolio, bag, or case of any design, and that such changes in the precise embodiment thereof may be made as come within the scope of the claims.

I claim:—

1. As an article of manufacture, a case having a handle secured thereto, a cover for the case adapted to fold thereover, means for engaging the free end of said cover when folded over the case, a cut out portion in said cover to permit the passage of the same over the handle without interfering therewith, a flap formed by said cut out portion, and fastening means carried by one end of said flap for engaging the adjacent end of said cut out portion substantially as described.
2. As an article of manufacture, a case having a handle secured thereto, a cover for the case and adapted to be folded thereover, means for engaging the free end of said cover when folded over the case, said cover having a cut out portion therein to permit the passage of the same over the handle without interfering therewith, and a flap

formed by said cut out portion to present an unbroken surface, substantially as described.

3. As a new article of manufacture, a case having handles secured to the sides thereof and one side continued therefrom to provide a flap cover adapted to pass over the case and be tucked in a pocket formed on the other side of the case, a cutout portion in the cover to permit the handle on the said other side of the case to be outward thereof, and a flap formed by said cutout portion and having fastening means on its free end to engage the adjacent edge of the cutout portion of the cover when the same is in place.

4. As a new article of manufacture, a case having handles secured to the sides thereof, one of said sides being continued to provide a flap cover, a cutout portion in said cover to permit the passage of the cover over the handle without interference therewith, a flap formed by said cutout portion, and a clasp fastening on the free end thereof for engaging the adjacent end of said cutout portion, and said flap being cut away at its sides to provide handle receiving openings.

In testimony that I claim the foregoing I have hereunto set my hand at Milwaukee, in the county of Milwaukee and State of Wisconsin.

LAWRENCE A. OLWELL.
